DEVICE FOR SECURING HEADS TO
BARRELSHoward L. Newton, Wauwatosa, Wis., assignor to
Pressed Steel Tank Company, Milwaukee, Wis.,
a corporation of Wisconsin

Application April 22, 1936, Serial No. 75,721

5 Claims. (CL. 220—61)

This invention relates to a device for securing a removable head to a barrel.

One of the objects of the invention is to provide a device of this character which is so constituted and organized that it may be conveniently applied and released and yet is of simple, durable and compact construction.

In carrying out the present invention, an operating screw is employed for contracting and expanding the ring and has combined therewith the crank handle in such a novel manner that the handle may be conveniently used after the manner of a high speed wrench to cause the screw to contract or expand the ring. When not in use the handle may be compactly folded against the head of the barrel and is releasably retained in such position. Hence, the handle does not present any projection which is likely to be injured or which interferes with convenient shipping of the complete barrel head and its closure device.

Other objects and advantages reside in certain novel features of the construction, arrangement and combination of parts which will be hereinafter more fully described and particularly pointed out in the appended claims, reference being had to the accompanying drawing, forming a part of this specification, and in which:

30 Figure 1 is a view in top plan showing a head equipped with a closure device embodying the present invention; and

Figures 2 and 3 are sectional views taken on lines 2—2 and 3—3 of Figure 1.

35 Referring to the drawing, the numeral 1 designates a metallic receptacle or container which may be a barrel. The upper end of the barrel is open and has its periphery provided with a rolled bead 2. A removable head 3 is provided for the upper end of the barrel. The head 3 is of cupped formation and is provided with a curved flange-like structure 4 around its periphery adapted to engage a gasket 5 interposed between the flange structure 4 and the rolled bead 2.

40 The head is fastened in position to close and hermetically seal the open end of the barrel by means of a split clamping ring 6. This ring is constructed of resilient sheet metal of appropriate gauge and it is of channel or concave form so that when it is applied its upper portion 7 bears down on the flange structure 4 of the head and its lower portion 8 engages under the rolled bead 2.

45 Adjacent its ends the ring 6 is provided with inwardly extending apertured lugs 9 and 10 which

overlie the cupped portion of the head 3. An operating screw 11 is provided and has the threaded portion of its shank interengaged with internal threads provided in the lug 9. The screw also has a smooth portion of its shank extending through a smooth opening provided therefor in the lug 10. This screw is constrained against axial movement relative to the lug 9 by means of a collar 12 fixed thereto and engaging one side of the lug 10 and its head 13 which is also fixed to the shank and engages the other side of the lug 10. In other words, the screw is threadedly connected with the lug 9 and is swiveled to the lug 10.

50 An operating handle 15 is provided and is in the form of a crank having a suitable hand grip 16 at one end and having its other end permanently connected by a universal joint designated at 17 to the head of the screw 11. The universal joint 17 comprises a part 18 secured to one end 55 of the crank handle and straddling and pivotally connected as at 19 to a second part 20 which, in turn, is pivotally connected to the bifurcated head 13 of the screw 11. The pivotal connection between the part 20 and the head 13 is at right angles to the pivot 19.

55 For the purpose of releasably securing the handle 15 in position close up against and parallel to the head 3 during shipment and storage, a keeper 25 is integrally formed or rigidly secured to an intermediate portion of the ring 6. This keeper presents an inwardly and horizontally opening socket and is so positioned that this socket receives the curved portion 16' of the handle 15. The handle 15 is releasably retained in the keeper 25 by means of a suitable pin 26 which has its head 27 resting on the lower wall of the keeper and its shank extending up through an opening in the upper wall thereof. To release the handle from the keeper the portion of the pin 26 which projects above the keeper must be grasped and the pin pulled upwardly until its head is received in the counter-sink 28 provided therefor in the upper wall of the keeper at which time the crank handle may be swung out of the keeper and then raised to a position where it may be conveniently operated to tighten up or release the screw.

60 While I have shown and described one construction in which the invention may be advantageously embodied, it is to be understood that this construction has been selected merely for the purpose of illustration or example and that various changes in the size, shape and arrangement of the parts may be made without departing from 65

the spirit of the invention or the scope of the subjoined claims.

The invention claimed is:

1. A device for securing a removable head to a barrel comprising a split clamping ring, lugs secured to end portions of the ring and projecting inwardly over the barrel, an operating screw swiveled to one of the lugs and threadedly interconnected with the other, a crank handle, and a universal joint permanently connecting one end of the crank handle to the screw.
2. A device for securing a removable head to a barrel comprising a split clamping ring, lugs secured to end portions of the ring and projecting inwardly over the barrel, an operating screw swiveled to one of the lugs and threadedly interconnected with the other, a crank handle, a universal joint permanently connecting one end of the crank handle to the screw, said crank handle being foldable to a position parallel to the head when not in use, and a keeper engageable with the crank handle to hold it in folded position.
3. A device for securing a removable head to a barrel comprising a split clamping ring, lugs secured to end portions of the ring and projecting inwardly over the barrel, an operating screw swiveled to one of the lugs and threadedly interconnected with the other, a crank handle, a universal joint permanently connecting one end of the crank handle to the screw, said crank handle

being foldable to a position parallel to the head when not in use, a keeper engageable with the crank handle to hold it in folded position, said keeper presenting an inwardly opening socket and being positioned to engage a curved portion of the crank handle, and releasable means for retaining the crank handle in the keeper.

4. A device for securing a removable head to a barrel comprising a split clamping ring, screw means cooperable with end portions of the ring for expanding and contracting the same and a crank handle having a universal connection with the screw means and manipulated to operate the same, said crank handle also being foldable to a position within the confines of the barrel, and means for releasably retaining the handle in its folded position.

5. A device for securing a removable head to a barrel comprising a split clamping ring, a screw interconnected with the end portions of the ring and operable when turned to expand and contract the ring depending upon the direction in which the screw is turned, an operating handle, and a universal joint between the handle and one end of the screw to positively and permanently interconnect the handle and screw, and also to provide for folding of the handle to an inoperative position within the confines of the barrel.

HOWARD L. NEWTON. 30
